UNITED STATES PATENT OFFICE.

PAUL M. HOTCHKIN, OF CHICAGO, ILLINOIS.

SWITCH-BOX.

1,164,349.

Specification of Letters Patent. Patented Dec. 14, 1915.

Application filed November 23, 1914. Serial No. 873,466.

To all whom it may concern:

Be it known that I, PAUL M. HOTCHKIN, residing at Chicago, in the county of Cook and State of Illinois, have invented certain 5 new and useful Improvements in Switch-Boxes, of which the following is a specification.

My invention relates to a switch-box of a construction suitable to be used in conjunction with a lighting system, for illuminating show-cases, display counters, and similar structures, but it of course will be obvious after an understanding thereof is had that the device is well adapted for other uses as 15 well as those mentioned.

The primary object of my invention is the provision of a switch-box that is adapted to readily fit into the supporting frame work or the body of a show case or display 20 counter and be conveniently connected with a conduit through which the current wires pass.

Another object of my invention is to so construct and arrange the parts of a switch-box that it is reversible,—that is it may be fitted either to the right or left side of a counter structure and receive the conduit either from above or below.

Still another object is the provision of a 30 switch box that is adapted to be fitted with a push button switch of any of the well-known commercial types. And further objects are the provision of a switch-box that is inexpensive to manufacture, effective in 35 performing the various functions for which it is designed, and which is neat and attractive in appearance.

These and other objects I prefer to accomplish by the means and in the manner 40 hereinafter fully described and as more particularly pointed out in the claims reference being had to the accompanying drawings forming a part of this specification, wherein,

Figure 1 is a vertical front elevation of my 45 switch-box installed as a right hand fitting at the lower end of an electric conduit for a show case lighting system. Fig. 2 is a longitudinal central section of my switch box taken on line 2—2, Fig. 1, and looking in 50 the direction indicated by the arrows, the switch being shown in full elevation therein.

Referring to the drawings, similar reference characters indicate the same parts throughout the several figures.

55 In the drawings 5 represents a vertical

standard or rear corner post of a show-case or display counter that has the metal tube or conduit 6 from the lighting system thereof disposed upon and secured to its outer surface in any suitable manner so that its 60 lower end terminates adjacent the floor upon which the show case is placed. My switch box, which is adapted to be connected to this lower end of the conduit, preferably comprises a housing or casing of substantially rectangular shape and consists of a bottom or rear wall 7, end walls 8 and 9, and longitudinal side walls 10 and 11 all 65 preferably formed integrally of one piece of cast metal.

End wall 9 is preferably slightly shorter than the opposite end wall and is provided with a lateral extension 12 that projects at right angles thereto and is of substantially the same relative dimensions as said end 70 wall 9, that is, it is of same width as said wall and projects therefrom a distance approximately corresponding with the depth of said wall. The longitudinal sides of the extension are flared upwardly to provide 75 lips or flanges 13 extending the length thereof and are of a height sufficient to bring their upper outer surfaces flush with the outer edges of the side walls 10 and 11 of which they are adapted to form an exten- 80 sion or continuation.

At the outer end of extension 12 is formed a hollow substantially cylindrical embossment 14 that is preferably offset therefrom a suitable distance and is cast integral therewith as shown. The longitudinal wall of 85 this embossment is preferably thickened for the purpose of forming a vertical shoulder 90 15 the function of which will hereinafter more fully appear. Opposite the shoulder 15 and adjacent the extension 12 the wall of the embossment is cut away to form a longitudinal vertical slot 16. Screw lugs 17 and 18 are cast integral respectively with 95 end wall 8 adjacent its outer edge and at 100 the juncture between the end wall 9 and the extension for the purpose of supporting a switch 19 of any suitable design. A longitudinally elongated metal plate 20 is employed as a cover for the switch box and is provided with openings through which the push buttons of the switch pass and which has its longitudinal edges and its end edge adjacent wall 8 overhang the walls of the switch box substantially as shown. The edge 105 110

115

of the cover plate adjacent the embossment 14 is preferably flared outwardly as shown at 21 to close the slot 16 in said embossment. Said cover plate fits snugly over the walls 5 of the box and the flared edges of the extension.

Embossment 14 is bored out longitudinally and has its end internally threaded, the upper end to receive the conduit 6 and 10 the lower end closed by a suitable plug 22, which latter is adapted to be removed and tapped into the opposite end of said embossment when the conduit is secured to the end opposite that shown.

15 In installing the box I prefer to cut a shallow recess 23 in the adjacent portion of the standard or post for the purpose of seating the extension and after placing the same therein to secure it in place by a screw 23 passing through the extension and a screw 24 passing through the corner formed by the juncture between said extension and the adjacent end wall of the box. The wires 20 x and y from the conduit 6 pass into the embossment through the hollow extension, through the switch and switch-box and leave the same through an insulated opening 25 in the rear or bottom wall as will be seen.

While I have herein illustrated and 20 described certain specific means for carrying out my invention, it of course will be obvious to others skilled in the art to which it pertains, that various modifications or refinements thereof are possible without materially departing from the spirit of my invention. I therefore desire it understood that all such obvious changes or modifications are contemplated within the scope of my invention as expressed in the following 35 claims.

Having described my invention what I claim as new and desire to secure by Letters Patent is,—

1. A device of the kind specified comprising 45 a housing for a switch consisting of rear, side and end walls, a channeled extension projecting laterally from one of said walls and having upturned edges, and a hollow embossment adjacent one end of said extension that communicates with said extension and to which a conduit is adapted to be connected.

2. A device of the kind specified comprising 55 a housing for a switch consisting of rear, side and end walls, a channeled extension projecting laterally from one of said walls and having upturned edges, a hollow embossment adjacent one end of said extension that communicates with said extension and to which a conduit is adapted to be connected and a cover common to said housing and said extension.

3. A device of the kind specified comprising 65 a housing for a switch consisting of a rear, side and end walls, a channeled exten-

sion projecting laterally from one of said walls and having upturned edges, and a hollow embossment adjacent one end of said extension, said housing, extension and embossment cast integrally in one piece of 70 metal.

4. A device of the kind specified comprising a housing for a switch consisting of a rear, side and end walls, a channeled extension projecting laterally from one of said walls and having upturned edges, a hollow embossment adjacent one end of said extension, said housing, extension and embossment cast integrally in one piece of metal, 75 and a cover common to said housing and extension.

5. A device of the kind specified comprising a housing for a switch consisting of rear, end and side walls, means for securing a switch therein, a hollow extension projecting from one of said walls and communicating with said housing, and a hollow enlargement on said extension that is provided with a cut-away portion through 85 which communication is had with said extension.

6. A device of the kind specified comprising a housing for a switch consisting of a rear, end and side walls, means for securing a switch therein, a hollow extension 95 projecting from one of said walls and communicating with said housing, a hollow enlargement on said extension that is provided with a cut-away portion through which communication is had with said extension, and a cover common to said housing and extension that is provided with an upturned end that partially closes the cut-away portion of said embossment.

7. A device of the kind specified comprising 105 a housing for a switch consisting of rear, end and side walls, means for securing a switch therein, a hollow extension projecting from one of said walls and communicating with said housing, and a hollow 110 enlargement on said extension that is provided with a cut-away portion through which communication is had with said extension, the walls of said housing, said extension, and said embossment cast integrally 115 in one piece of metal.

8. A device of the kind specified comprising 120 a housing for a switch consisting of rear, end and side walls, means for securing a switch therein, a hollow extension projecting from one of said walls and communicating with said housing, a hollow enlargement on said extension that is provided with a cut-away portion through 125 which communication is had with said extension, the walls of said housing, said extension, and said embossment cast integrally in one piece of metal and a cover common to 130 said housing and said extension that is provided with an upturned end that par-

tially closes the cut-away portion of said embossment.

9. A device of the kind specified comprising a housing for a switch consisting of rear, side and end walls, a channeled extension projecting laterally from one of said walls and having upturned edges, and a hollow embossment adjacent one end of said extension that communicates with said extension and to which a conduit is adapted to be connected, said housing provided with an opening in one of its walls through which the wires from said conduit pass.

10. A device of the kind specified comprising a housing for a switch consisting of a rear, side and end walls, a channeled extension projecting laterally from one of said walls and having upturned edges, and a hollow embossment adjacent one end of said extension, said housing, extension and

embossment cast integrally in one piece of metal, and said housing provided with a lateral outlet opening in one of its walls.

11. A device of the kind specified comprising a housing for a switch consisting of 25 rear, side and end walls, a channeled extension projecting laterally from one of said walls and having upturned edges, and a hollow embossment adjacent one end of said extension that communicates with said 30 extension and to which a conduit is adapted to be connected, the rear wall of said housing being provided with an outlet opening for the wires from said conduit.

In testimony whereof I have hereunto set 35 my name in the presence of two witnesses.

PAUL M. HOTCHKIN.
